V. HOWARD

SPARK ARRESTER

Filed March 17, 1924

Fig. 2.

INVENTOR.
Valgene Howard.

BY

Clayton E. Wyrick
ATTORNEY.

UNITED STATES PATENT OFFICE.

VALGENE HOWARD, OF FLINT, MICHIGAN.

SPARK ARRESTER.

Application filed March 17, 1924. Serial No. 699,958.

This invention relates to spark arresters and has for one of its objects, the provision of a device for arresting the discharge of sparks or the like from the chimney, and to combine in a unitary relation with a spark arrester, a means for increasing draft in the chimney to which the arrester is applied.

A further object is to entrap any large fragments of ignited material rising with the draft, such as scraps of paper, in advance of the spark arrester, proper, the latter being proportioned to prevent the escape of relatively small ignited particles.

A still further object of the invention is to provide, a simple means, for securing the spark arrester in a substantial manner to the chimney coping.

The above and other objects will be apparent from the following description wherein reference is made to the accompanying drawings, illustrating a preferred embodiment of my invention.

In the drawings:

Figure 1 is a view in side elevation, partially in section of the improved spark arrester applied to a chimney.

Figure 2 is a top view of the same, partially in section, on line 2-2 of Figure 1.

In these views, the reference character 1 designates a chimney, provided at its top with the usual outwardly projecting coping 2. The invention surmounts said chimney by an enclosure 3, formed of wire screen or other foraminous material, preferably cylindrical.

To said enclosure is rigidly connected the sheet metal base 4 and cover 5, the latter being preferably conical. Angle-iron rings 6 and 7 may be employed to secure to said enclosure the cover and base thereof, said rings being riveted or otherwise suitably secured to the parts which they connect.

The base 4 is comprised of a rectangular sheet-metal plate having a central circular opening, the corners of said base being cut away (see Figure 2) and its marginal portions being downturned to embrace the coping 2 of the chimney, and bent beneath said coping, as indicated at 8, to positively hold said base (and the entire spark arrester) in place.

Through the apex of the cover 5 is passed a vertical shaft 9, journaled in bearings 10 and 11, the former being directly interiorly

carried by said cover, and the latter being supported by the cover, somewhat below the latter, through a plurality of arms 12.

Said shaft is adapted to be wind-driven by a vane wheel 13, fast thereupon above the cover, said wheel being of any suitable construction. Upon the lower end of said shaft, just above the base 4, is mounted a fan 14, which when said shaft is driven supplements the natural draft prevailing in the chimney 1. Above said fan and centrally within the enclosure 3, a plurality of large radial vanes 15 are fast upon the shaft 9.

From the base 4, there rigidly depends a sheet metal cylinder 16, open at its ends and having its upper end registering with the central opening of said base. Said cylinder is spaced from the chimney 1, and is formed with perforations 17 of larger area than the openings of the enclosure 3, a similar circle 18 of such perforations being formed in the base between said cylinder and enclosure.

In the use of the described invention, any relatively large fragments of paper or other burning material that may be carried up the chimney will, in most cases ascend close to the wall thereof. Such fragments, therefore, will be trapped between the cylinder 16 and said wall and will burn harmlessly.

The large perforations 17 and 18 allow the heated air and gases of combustion to rise freely through the space between said cylinder and the chimney wall, so as to carry such large fragments into this space.

Sparks and relatively small burning fragments, rising into the enclosure 3 will lodge against the screen wall of said enclosure, while the heated air and gases will pass freely through said wall. Such of said sparks and fragments as encounter the rotating vanes 15 will be thrown by the latter forcibly against the screen wall, and will be more or less extinguished by impact with said vanes.

The fan 14 will intensify the draft more or less according to the velocity of the wind and the resulting rotational speed of the shaft 9.

The described attachment of the device to the chimney coping is very secure and may be quickly established.

From the foregoing description it becomes evident that the device is very simple and efficient in operation, will not easily get out

of order, operates automatically and provides a device which accomplishes the objects described.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

Having thus described my invention, I claim:—

1. A spark arrester comprising a base adapted to be superposed upon a chimney, an inclosure attached to said base thereabove having a foraminous wall, and adapted to communicate through the base with the chimney and a perforated cylindrical mem-

ber carried by said base therebeneath, adapted to depend into said chimney in spaced relation to the wall thereof.

2. A spark arrester comprising a base engageable with the outlet end of a chimney, a foraminous inclosure secured to said base and projecting upwardly therefrom, and a cylindrical member projecting downwardly therefrom and having perforations exceeding in size the openings in the foraminous inclosure, and adapted to form with the inner wall of the chimney a trap for the larger ignited particles carried up through the chimney and said foraminous wall retaining the smaller particles.

In witness whereof I hereunto set my hand.

VALGENE HOWARD.
